J. E. HENTHORN

PROTECTOR FOR SHOES

Filed Sept. 15, 1922

INVENTOR.

James E. Henthorn
By his Attorney,
Wilson M. Howard

UNITED STATES PATENT OFFICE.

JAMES E. HENTHORN, OF CAMDEN, NEW JERSEY, ASSIGNOR TO UNITED SHOE MACHINERY CORPORATION, OF PATERSON, NEW JERSEY, A CORPORATION OF NEW JERSEY.

PROTECTOR FOR SHOES.

Application filed September 15, 1922. Serial No. 588,404.

To all whom it may concern:

Be it known that I, JAMES E. HENTHORN, a citizen of the United States, residing at Camden, in the county of Camden and State 5 of New Jersey, have invented certain Improvements in Protectors for Shoes, of which the following description, in connection with the accompanying drawings, is a specification, like reference characters on the drawings indicating like parts in the several figures.

This invention relates to the protection of shoes against soiling or damage during manufacture, as by the use of a covering of 10 textile or other suitable material.

During the manufacture of many shoes, especially light colored shoes, it is considered necessary to provide a protector or cover, to prevent the soiling and marring of the upper materials. Usually a paper or cloth cover is made up approximately in the shape 20 of the upper of the shoe and is assembled and lasted together with the upper materials. When the shoe is finished such a cover 25 is removed by tearing it down the front and back of the shoe and then cutting it away by a hand knife which cuts against the top face of the welt. This procedure involves the discarding of the cover after a single 30 use, there is considerable danger of marring the welt in cutting the cover away, and the operation of cutting it away is slow and tedious because of the care required.

An object of the present invention is to 35 facilitate the protection of shoes by obviating the above and other difficulties, as is hereinafter explained in detail.

From one point of view, the invention may be regarded as comprising a novel cover 40 for shoes having a portion of textile material extending around adjacent its bottom edge, which portion has a part having threads extending only in a direction perpendicular to the edge of the cover. That 45 is to say, this part of the cover is provided with the usual filling or woof threads but has no warp threads extending parallel to the edge of the cover. When a cover of this construction is used in protecting a 50 shoe, the lasting tacks, staples, inseam stitches, or other fasteners may pass through this part of the cover and will hold it firmly in place to protect the shoe upper. During the inseam trimming operation the edge

of the cover is trimmed down so that only 55 the ends of these filling threads, caught in the inseam or equivalent sole-attaching fastenings, hold the cover on the shoe; by this arrangement the cover may readily be pulled off without any further cutting operation 60 when the shoe is finished, the filling threads pulling out easily from the inseam which holds them.

Preferably the prepared part of the cover which has its threads running in a direction perpendicular to the edge of the cover 65 will be strengthened by a suitable stiffening material, as for example dried paste or heel stain, so that it will have sufficient body to stand up during the lasting and inseaming 70 operations.

In the illustrated construction of such a cover the upper and lower parts of the cover are made separate and are connected, as for example by a chain-stitch seam, so that after a shoe is finished the bottom part of 75 the cover may be removed and a new bottom portion, in the form of a suitable piece of tape, substituted therefor, the upper part of the cover being used a plurality of times. 80

From another point of view my invention may be regarded as an improved method of protecting shoes involving the steps of enveloping the upper part of a shoe in a cover of the type described above, and during the 85 inseam trimming operation removing that part of the cover which extends beyond the inseam and which up to that time prevents removal of the cover without cutting. By this method of procedure, it is unnecessary 90 to cut or tear the cover in any way after the shoe is finished as it can readily be pulled off without the use of any tools.

The above and other novel aspects of my invention will be apparent from the following description of the invention as illustrated in the accompanying drawings, in which—

Fig. 1 is a perspective view of a finished shoe from which a cover is being removed; 100

Fig. 2 is a perspective view showing the prepared tape which I prefer to use, before and after the application of the stiffening material which I find described;

Fig. 3 is a view showing the bottom part 105 of a cover constructed according to my invention;

Fig. 4 is a cross-section of the tape shown

in Fig. 2 substantially on the line 4—4 in that figure;

Fig. 5 is a perspective view showing the operation of inseaming a shoe, the upper of which is enveloped in a cover of the type described; and

Fig. 6 is a perspective view of part of a lasted shoe showing the inseam trimming operation.

- 10 As described above, I prefer to use a two-part cover made up of an upper part 10, which may be of any suitable construction, and a lower part 12 comprising a specially prepared tape secured to the bottom margin 15 of the part 10 by means of a chain-stitch seam. A cover of this type may be assembled with the upper of a shoe by means of suitable clips 14 or otherwise, and lasted with the upper into the position illustrated 20 in Fig. 5, as is customary with covers previously in use. It will be recognized, however, that my invention is not limited to the use of a two-part cover such as is illustrated. The prepared tape 12 is formed in any suitable manner with edge portions 16 of suitable textile material, such as canvas, connected by an intermediate portion 18 which has filling or woof threads connecting the two parts 16, but which is made up without 25 any warp or longitudinal threads running parallel to the edge of the tape.

In order to give the part 18 sufficient body to enable it to stand up during the operations of lasting and inseaming a shoe, I prefer to impregnate this part of the tape with a suitable stiffening material as shown diagrammatically at 20 in Fig. 2. This stiffening material may be in the form of any suitable paste or liquid which on drying will 30 sufficiently stiffen the filling threads in the part 18 so that they will not be too limp for convenient manipulation; in practice I have found the usual commercial heel stain to be a satisfactory material for this purpose. 35 The tape prepared as illustrated in Fig. 2 is attached to the bottom of the cover 10 by means of a chain-stitch seam 22 which can be pulled out to remove the upper part of tape 12 after the cover has been used to permit a new tape to be attached to the cover 10 so that it may be used a second time.

In using a cover of this type, it is assembled about the upper of a shoe and lasted simultaneously therewith as is customary with the covers heretofore in use. After the pulling-over and lasting operations the lasting tacks pass through the stiffening part 18 and hold the cover in place during the upper trimming operation. 40 After the upper stapling operation, the cover is held in place by staples 24, as shown in Fig. 5, while after the inseaming or welt-attaching operation the inseam stitches 26 secure together a welt 28, the portion 18 of 45 the cover, an upper 30, and the sewing rib

32 of an insole, all arranged in the usual order. As shown in Fig. 6, during the inseam trimming operation the margin of the upper 30 is removed, either with or without a portion of the sewing rib 32, and the cover 70 is separated into two parts along a line passing longitudinally through the portion 18 to remove the lower portion 16 shown in Fig. 3, and a part of the portion 18. Prior to the inseam trimming operation the lower portion 16 shown in Fig. 3 prevents removal of the cover, but after that operation has been performed the cover can be removed at any time without further cutting since the cut threads of portion 18 can readily be 80 pulled out from the stitches of seam 26 and from under staples 24.

After the shoe has been prepared as illustrated in Fig. 6, an outsole 34 is attached and the shoe is finished in the usual manner. 85 When the shoe reaches the packing room, otherwise ready for cleaning and packing, the cover is removed by pulling out the threads of the portion 18 as illustrated at the right hand part of Fig. 1. Thereafter, if the cover has been made in two pieces as illustrated, the remainder of the portion 12 may be removed by pulling out the seam 22, a new piece of tape 12 attached, and the cover sent back for further use.

While one particular manner of practicing my invention has been illustrated and described, it is not my intention to limit its scope thereby or otherwise than by the terms of the appended claims. It is especially to be noted that it is not limited to use with welt shoes only, although it is found convenient to illustrate a shoe of that type in the drawing.

Having described my invention, what I claim as new and desire to secure by Letter Patent of the United States is:

1. A shoe cover adapted to conform approximately to the shape of a shoe upper and having its lower marginal portion comprising threads extending in one direction only for the reception of fastenings to secure the cover about a shoe.

2. A shoe cover adapted to conform approximately to the shape of a shoe upper and having its lower marginal portion comprising threads extending only in a direction perpendicular to the edge of the cover for the reception of fastenings to secure the cover about a shoe.

3. A shoe cover adapted to conform approximately to the shape of a shoe upper and having its lower marginal portion comprising threads extending in one direction only for the reception of fastenings to secure the cover about a shoe, and a second portion beyond said threads comprising both warp and filling threads.

4. A shoe cover adapted to conform approximately to the shape of a shoe upper

- and having its lower marginal portion of textile material made up of warp and filling threads, connected with the body of the cover by a portion made up of filling threads only to receive fastenings to secure the cover about a shoe.
5. A reusable shoe cover comprising a body part and a replaceable tape secured about the margin of the body part, said 10 tape having a portion made up of threads extending in one direction only to receive fastenings to secure the cover about a shoe.
6. A shoe cover adapted to conform approximately to the shape of the upper of a 15 welt shoe and having a portion arranged to receive the inseam stitches, said portion being composed solely of threads arranged to extend crosswise of the inseam.
7. A tape for use in making a shoe cover 20 of the class described comprising two portions of textile material made up of warp and filling threads connected by a portion having filling threads only, the connecting portion being impregnated with a stiffening 25 material.
8. That method of protecting shoes which comprises the steps of enveloping a shoe on a last in a cover which has a portion made up of threads extending in one direction 30 only, lasting, stapling and inseaming the shoe with the lasting tacks and the staples and the inseam stitches passing through said portion of the cover, trimming the inseam of the shoe in a manner to remove the 35 margin of the cover extending beyond said portion, finishing the shoe, and finally removing the cover by pulling out the cut threads of said portion from the inseam 40 stitches.
9. That method of protecting shoes which comprises the steps of enveloping a shoe on a last in a cover having a portion formed 45 with filling threads only, and another portion extending to the edge of the cover beyond said first portion and having both warp and filling threads, lasting and inseaming the shoe with fastenings passing through said first portion, trimming the inseam of the shoe in a manner to remove said second portion and cut the threads of 50 said first portion, and then finishing the shoe and removing the cover by pulling out the cut threads of said first portion as described.
10. That method of protecting shoes 55 which comprises the steps of enveloping a shoe on a last with a cover having a portion made up of threads extending in one direction only, securing the cover in place by fastenings extending through said portion and engaging the threads thereof, bottoming and finishing the shoe, and then removing the cover by pulling out the threads of said portion from the fastenings holding them in place.
- 60
11. That method of protecting shoes which comprises the steps of enveloping a shoe on a last with a cover having a first portion made up of threads extending in one direction only and a second portion 65 beyond said first portion and extending to the edge of the cover and made up of both warp and filling threads, by the use of fastening means engaging only the threads of said first portion, then removing said 70 second portion and cutting the threads of said first portion by a trimming operation, bottoming and finishing the shoe and removing the cover when desired by pulling out the cut threads of said first portion engaged by the fastening means.
- 75
- 80
- In testimony whereof I have signed my name to this specification.
